INNERSOLE AND METHOD OF MAKING THE SAME

Fred L. Ayers, Watertown, Mass.

Application January 25, 1943, Serial No. 473,453

6 Claims. (Cl. 36—22)

In my application for United States Letters Patent, Serial No. 480,320 for Innersole and method of making the same, filed March 24, 1943, there is disclosed an innersole having an inseam receiving rib comprising a longitudinally folded strip, preferably of fabric, provided with a reinforcing element within the fold, upper materials being secured to this rib beneath the reinforced portion which is thereafter removed during the inseam trimming. The part of the rib remaining after the trimming operation comprises two, or if a sole reinforcing layer is employed, three layers of fabric, the inseam being positioned close to the cut edges of these layers. When the outersole is to be cemented on, this cement saturates the fabric layers, which are thus so reinforced that the securement of the upper materials to the innersole and these parts to the outersole is amply strong. When the outersole is to be attached by outersole stitches, securing the outersole to a welt, which in turn is secured to the lasted shoe entirely by the inseam, a more secure attachment of the inseam to the lasted shoe than is afforded by the two or three layers of the fabric of the innersole rib, may be found desirable.

In accordance with this invention, therefore, the fabric rib of the construction heretofore described is reinforced by one or more other layers which may also be of fabric. This provides at least two additional layers to the rib which materially increases the "body" of the rib through which the inseam passes by which the welt and upper materials are secured to the lasted shoe.

For a more complete understanding of this invention, reference may be had to the accompanying drawing in which

Figure 1 is an inverted perspective view of an innersole embodying the invention.

Figure 2 is a detail sectional view on line 2—2 of Figure 1.

Figure 3 is a fragmentary sectional view similar to a portion of Figure 2 but showing a modification.

Figure 4 is a perspective view of the strip material of which the stitch-receiving rib is composed.

Figures 5 and 6 are views similar to Figure 4, but illustrating modified constructions.

Figure 7 is a top plan view of the strip guide by which the strip of Figure 4 is formed up and presented to the innersole blank for attachment thereto and shows a portion of the strip therein.

Figures 8, 9 and 10 are detail sectional views on the correspondingly numbered section lines of Figure 7.

Figures 11 and 12 are detail sectional views through one side portion of the lasted shoe before and after the inseam trimming operation, respectively.

Figure 13 is a view somewhat similar to Figure

5, but showing another manner of forming a reinforcing strip for the rib.

Referring to the accompanying drawing, at 1 is shown an innersole blank which may be of any suitable, preferably thin material, and to the lower face of which an inseam-receiving rib is secured. As shown in Figure 4, this rib may comprise a plurality of superposed strips 2 and 3, as shown as of fabric, the strip 3 being considerably narrower than the strip 2 and preferably of relatively non-stretchable material such as straight cut tape, while the strip 2 is preferably bias tape. They are secured together in superposed relation as by a line of fastenings such as stitches at 4, which confines the strips together along a narrow zone substantially centrally of the width of the strip 3, but preferably somewhat to one side of the center of the strip 2. Instead of securing the strips together by stitches, they may be cemented together as shown in Figure 5, and in order to facilitate subsequent folding up, the narrow strip may be in two pieces 3a, or if desired, one only of these pieces 3a, preferably the inner piece, may be used. If more body to the stitching rib is desired, a plurality of superposed narrow strips may be employed as shown in Figure 6. When more than one narrow strip is employed in superposed relation, stitching or stapling of the strips is preferable to cementing, in view of the difficulty of sufficiently localizing the attachment so as to permit the strips to be folded together readily along the zone or line of securement.

Instead of employing a fabric or tape reinforcement to the stitching rib, such a reinforcement may comprise a suitable plastic which may be extruded onto the bias tape as a narrow strip or ribbon 5 (Figure 13) as from a nozzle 6, such narrow strip being in lieu of one of the strips 3a of Figure 5, the line of fold of the bias tape 2 when the rib is formed being along one edge of the plastic strip so that it does not interfere with such folding. This plastic may be of cellulosic or any other composition which will set to film or strip form sufficiently rapidly after emerging from the nozzle.

The edge portions of the strips when secured by stitching are left free in order that they may slide relative to each other as they are bent to folded condition. Such bending or folding may be accomplished by passing the strips thus secured together through a guide member 10, illustrated best in Figures 7 to 10. This guide member consists of a block 11 having at one end a curved depression extending from side to side as at 12, this depression merging gradually into the contour shown in Figure 10 where there is a flat substantially rectangular depression 13 adjacent to the top surface of the block 11 and a depending U-shaped depression 14 at one side of the center of the depression 13. Cooperating

with the block 11 is a cover member 15 which, at the entering end of the strip, is provided with a fin 17 which depends into the depression 12 and defines a line of fold for the strips 2 and 3. This fin 17 extends part way only toward the exit end of the guide and is so disposed that the narrow strip 3 is folded and enclosed by the portion 22 of the wider strip 2. Thus the wider strip is folded about the narrower strip or strips so that the stitching rib when presented to the base of the blank comprises at least three layers of fabric with outwardly extending flanges, each of the thickness of one layer of fabric, extending therefrom. When only three layers are used, at least two of them are cemented in face to face relation which adds to their combined strength.

The top surface of the strips 2 and 3 may be pretreated with a cement so that when the strips are thus folded up together, the sides of the folded strip 3 are united by the cement, and the flanges 20 and 21 when presented to the face of the blank, which is also cement treated, adhere thereto. The edges of the narrow strip 3 preferably terminate at or closely adjacent to the face of the blank 1, although if desired, of course, they could be extended to form portions of the attaching flanges. Ordinarily, however, this is not necessary to give a sufficiently good bond between the stitching rib and the innersole blank.

It will be noted that the wide flange 20 is positioned on the inside, the narrow flange 21 projecting toward the margin of the blank. While as shown in Figure 1 the stitching rib extends around the forepart and back through the shank to the heel seat, the extent may be varied in accordance with the type of lasting desired for the shank and heel, as it may terminate forwardly of the shank or may be extended around the heel seat as may be desired.

Where the stitching rib is cemented in position, it is usually preferable to employ a further reinforcing layer such as the fabric, as shown at 25, which extends across the face of the innersole between the portions of the rib on opposite sides and preferably is also brought up against the inner face of the rib to about the level of its upper edge. This reinforcing layer may also be of fabric, such as canvas, and be cemented in position. If desired, however, the inseam rib may be secured as by stitching as at 28, in which case there will ordinarily be no need for using the reinforcing fabric layer 25. Such a construction is illustrated in Figure 3. Where more than one strip, such as 3, is employed to be enclosed by the outer layer of fabric, each will be folded in so that the portion of the stitching rib which receives the inseam fastening such as stitches, staples, or the like, is composed of at least six thicknesses of strip material.

Where the inseam rib is secured by cement, the rib and the innersole blank may be fed together so that the rib is folded and applied progressively to the innersole blank, and for this purpose four-motion feeding needles 30 may be employed which extend and move through slots 31 of the guide. Where stitching is employed to secure the rib in position, these needles 30 will be provided with eyes, and threaded for the reception of the stitching threads, and ordinarily there will be a third needle to apply a third row of stitches 28 on the inner face of the rib, as shown in Figure 3.

When an innersole constructed in accordance with this invention is employed, the welt 35, and

lasted upper materials 36 and 37 are secured to the stitching rib as by the inseam stitches 40 as shown in Figure 11, and the inseam trimming removes the upper edges of these portions but leaves the several layers of fabric of which the inseam rib is formed as a relatively soft body to retain the inseam fasteners, such as stitches or staples, in position. This securing of the welt, upper materials, and innersole together, is ample so that when an outersole (not shown) is secured by outersole stitching to the welt 35, the securing of the outersole in position is ample, while the remaining portions of the innersole rib are sufficiently soft to provide the desired flexibility to the entire sole structure and may be so compacted as to avoid the necessity of employing a bottom filler.

From the foregoing description of certain embodiments of this invention, it should be evident to those skilled in the art that various changes and modifications might be made without departing from the spirit or scope of this invention.

I claim:

1. An innersole comprising a blank and an inseam rib secured to one face of said blank, said rib comprising a plurality of layers of sheet material folded longitudinally so that one layer envelops the next inward layer, the outer layer only having its margins separated to form flanges, said flanges being secured to said blank face, the others of said layers terminating substantially at said blank face.

2. An innersole comprising a blank and an inseam rib secured to one face of said blank, said rib comprising a plurality of layers of material secured together in face to face relation, at least one of said layers being folded longitudinally and enveloping the next inward layer, the outer layer only having its margins separated to form flanges, said flanges being secured to said blank face, the others of said layers terminating substantially at said blank face.

3. An innersole comprising a blank and an inseam rib secured to one face of said blank, said rib comprising a plurality of layers of fabric folded longitudinally so that one layer envelops the next inward layer, the outer layer only having its margins separated to form flanges, said flanges being secured to said blank face, the others of said layers terminating substantially at said blank face.

4. The method which comprises securing together along a narrow zone a plurality of superposed pieces of strip material, folding said strips longitudinally substantially along said zone and turning the margins of at least one of said strips away from each other to form a pair of flanges, and progressively presenting and securing said flanges to one face of an innersole blank.

5. The method which comprises securing together a plurality of superposed pieces of strip material, folding said strips longitudinally and turning the margins of at least one of said strips away from each other to form a pair of flanges, and progressively presenting and securing said flanges to one face of an innersole blank.

6. The method which comprises securing together by a line of fastenings a plurality of superposed pieces of strip material, folding said strips longitudinally substantially along said line and turning the margins of at least one of said strips away from each other to form a pair of flanges, and progressively presenting and securing said flanges to one face of an innersole blank.

FRED L. AYERS.
